UNITED STATES PATENT OFFICE.

JAMES H. COOK, JR., OF HOMER, MICHIGAN, ASSIGNOR OF ONE-HALF TO
HENRY O. COOK, OF SAME PLACE.

KNIFE.

SPECIFICATION forming part of Letters Patent No. 530,913, dated December 11, 1894.

Application filed January 29, 1894. Serial No. 498,407. (No model.)

To all whom it may concern:

Be it known that I, JAMES H. COOK, Jr., a citizen of the United States, residing at Homer, in the county of Calhoun and State of Michigan, have invented certain new and useful Improvements in Knives, of which the following is a specification, reference being had therein to the accompanying drawings.

The invention consists in the peculiar construction of a pocket knife, comprising a casing in which a blade slidingly engages, a pin secured to the blade extending through a slot in the casing and connected to a plate on the outside, which when turned at an angle to the casing may be employed as a handle to slip the blade in or out, and when turned parallel therewith forms a complementary portion to the handle when the blade is opened or closed.

The construction is designed to make what I call a safety pocket knife, that is one which cannot be closed on the hand when using it, also which is free from dirt by having the casing entirely inclosed when the blade is withdrawn and dispensing entirely with the use of springs.

The invention further consists in the peculiar construction, arrangement and combination of the various parts as more fully hereinafter described.

In the drawings, Figure 1 is a perspective view of my improved knife, showing the blade withdrawn and the cover or actuating plate turned slightly from its closed position. Fig. 2 is a plan view showing the blade partly extended. Fig. 3 is a vertical, central, longitudinal section therethrough, when the blade is entirely extended. Fig. 4 is a cross section on line $x-x$ of Fig. 2. Fig. 5 is a horizontal section through the connecting pin, showing the case in plan.

A is a casing closed on all sides, having the opening B at one end. C is a knife blade therein, of a length to be inclosed entirely within the casing.

D is a pin pivotally secured at the base or butt of the knife blade and having the flat portion E engaging through a longitudinal slot F in one of the side walls of the casing

A. At each end this slot is provided with an enlargement G which may have stops or shoulders H on opposite sides, against which the sides of the flat portion E of the pin is adapted to engage when turned at right angles to the slot.

I is a plate secured near one end to the outer end of the flat portion E of the pin and forming a handle, by means of which the blade may be extended from the casing or withdrawn therein.

J is a hook at one end of this plate adapted to form a cover for the open end B of the casing when the blade is withdrawn.

The parts being thus constructed their operation is as follows: In the closed position of the knife the hook J engages over the open end B of the casing and thus closes the only point through which dirt might find access to the interior, the plate proper covering the slot F. To open it, the operator turns the plate at right angles to the casing, in which position the flat portion E of the pin registers with the longitudinal slot F. Then using the plate as a handle, the knife blade may be slid out of the casing, as shown in Fig. 3. The plate may then be turned parallel with the casing, the hook portion engaging over the butt of the casing, as shown in Fig. 3, and forming a complementary portion of the handle. In this position the sides of the flat portion E of the pin engage against the shoulder H at the forward end of the slot, which securely locks the blade against being withdrawn.

To withdraw the blade the operator goes through the reverse operation, that is, turns the plate to a position at right angles to the casing, sliding the pin through the slot to the butt and then turning the plate upon the pivot, engaging the hook over the open end of the casing. In this position the pin engages against the shoulders H, of the enlargement G at the butt of the casing, which prevents the withdrawal of the blade until the plate is again turned at right angles to the casing. Thus I obtain a knife in which the blade is locked in its closed position, locked

in its open position and provided with a casing which is dust proof, obviating all use of springs and the trouble connected therewith.

Any desired shape of blade may be used 5 and the pin and plate may be varied also to cover any means of locking the pin by turning it in opening and closing.

What I claim as my invention is—

1. In a knife, the combination of a hollow case, a blade sliding therein, a pin extending from the base of the blade and entering a longitudinal slot in one side of the case, and a plate secured to the outer end of the pin, adapted to be turned at an angle to the case, and to form a handle to move the blade, when the blade is open or closed, substantially as described.
2. In a knife, the combination of a hollow casing, a blade sliding therein, a pin extending from the base of the blade through a longitudinal slot in the side of the casing, a plate secured to the outer end of the pin, and adapted to be turned at an angle or parallel 25 with the handle, and means for locking the

blade in its open and closed position by the movement of the plate, substantially as described.

3. In a knife, the combination of the hollow casing, open at one end, the blade slidingly 30 engaging therein, and a plate I pivoted to the outside of the casing having the hook J adapted to cover the open end of the casing when the plate is over the casing, substantially as described.

4. In a knife, the combination of the casing A, the blade C therein, the plate I, the pin connecting the butt of the blade with the end of the plate, and projecting through a slot in the casing, the hook J on the plate, 40 the enlargements at the ends of the slots having shoulders H, the parts arranged and operating substantially as and for the purpose described.

In testimony whereof I affix my signature in 45 presence of two witnesses.

JAMES H. COOK, JR.
